No. 758,934.

PATENTED MAY 3, 1904.

J. S. PURDY.
FOUNTAIN PEN.

APPLICATION FILED JAN. 15, 1903. RENEWED MAR. 23, 1904.

NO MODEL.

UNITED STATES PATENT OFFICE.

JOHN SOPER PURDY, OF BROOKLYN, NEW YORK.

FOUNTAIN-PEN.

SPECIFICATION forming part of Letters Patent No. 758,934, dated May 3, 1904.

Application filed January 15, 1903. Renewed March 23, 1904. Serial No. 199,627. (No model.)

To all whom it may concern.

Be it known that I, JOHN SOPER PURDY, of Brooklyn, in the county of Kings, and in the State of New York, have invented a certain new and useful Improvement in Fountain-Pens; and I do hereby declare that the following is a full, clear, and exact description thereof, reference being had to the accompanying drawings, in which—

10 Figure 1 is a longitudinal sectional view of a pen embodying my invention. Fig. 2 is a view showing in elevation the pen illustrated in Fig. 1. Fig. 3 is a transverse sectional view through the body of the pen looking toward the pen-point. Fig. 4 is a longitudinal sectional view through the point-section and parts attached thereto, and Fig. 5 is a longitudinal sectional view of the air-tube and cleaner.

20 The object of my invention has been to provide a fountain-pen which shall have, among others, the following advantages: of insuring a steady and uniform flow of ink, of being capable of using a soft and elastic pen-point, 25 of preventing the formation of air-bubbles, of insuring the proper admission of air into the pen-body, and of having its parts readily separated for the purpose of cleaning; and to such ends my invention consists in the fountain-pen hereinafter specified.

In carrying my invention into practice I provide a pen-body A, into which a ring B is screwed, the engagement being preferably by a right-hand thread. The ring B is provided with an internal thread b, which is preferably of an opposite character from that of the thread by which the ring engages the body and in the instance chosen for illustration is a left-hand thread. The thread b 40 preferably terminates at the base of a shoulder b', and a point-section C is screwed into the ring B by engagement with the thread b and preferably until the rear or upper end of the point-section comes in contact with the shoulder b'. The point-section is provided with a pen-slit c for the reception of the pen-point D. An ink-passage c' is formed in the lower portion of the point-section and extends from a flaring opening c² in its rear or upper end 45 forward and opens beneath the pen-point.

Above the pen a passage c³ is formed through the pen-section, and a tube E, preferably of metal, is inserted in the passage c³. The said tube has its forward end preferably flattened and bent down toward and close to the upper 55 surface of the pen-point, where it is provided with a slit e for the admission of air. A rod F is mounted in the tube E and at its lower or forward end is bent upward and extends through a slot e' in the tube E, the upwardly-bent end of the said rod serving as a handle f, by which the rod can be moved in the tube. The rear end of the said rod is provided with an eye f', which eye is engaged by an eye g, formed upon a rod G, the latter being preferably 60 formed of wire and of sinuous shape and extending through the passage c'. The length of the rod F is preferably such that its handle f can reach to the forward or lower end of the slot e' in the tube E, so that the eye upon the upper 65 or rear end of the rod will not contact with the adjacent end of the tube E and prevent movement of the rod until the said rod has reached the forward end of the slot e'. The rods F and G constitute cleaners. A sleeve H is secured, 70 preferably, upon the pen-section C, as by a threaded engagement, and such sleeve is provided with a reduced portion h for the reception of the cap I. If desired, the ring B can at its forward or lower end be provided with 75 a flaring opening for the reception of a conical shoulder c', formed upon the pen-section, and the sleeve can be screwed against said shoulder. The rear or upper end of the body is preferably provided with a central socket a, in 80 which is held, preferably by friction, a tube K, the tube being readily removable from its socket for the purpose of cleaning. The tube extends forward toward the forward end of the body, and at such end the tube is open. 85 The tube is also preferably provided with a metal sleeve k for protection and with openings k' through the tube and the sleeve. A rod L is loosely mounted in the tube K and at its forward or lower end is provided with 90 an enlargement or shoulder which, as illustrated, consists of cross-arms l, that prevent the said rod from entering the said tube beyond a given distance. If desired, the said cross-arms can be omitted.

In the operation of my fountain-pen the holder is filled with ink and the pen operated by the mere act of writing. The air will pass up the tube E and into the body of the holder and will cause a free flow of ink down the passage beneath the pen-point. The act of tipping the pen into writing position will cause the rod L to fall and break any bubbles which may have formed in the lower end 5 of the chamber in the pen. The presence of the wire G in the passage c' prevents a too ready flow of ink. Should the flow of ink be obstructed either by the clogging of the tube E or the passage c', the end of the rod F is engaged in any convenient manner—such, for instance, as by a hole i in the cap I—when the rod F and the wire G are caused to reciprocate in their respective tubes by moving the handle f' back and forth in the slot e'. 10 By the movement of the said handle the pen is conveniently and immediately relieved from any clogging and a proper flow of ink is immediately produced. Should any ink travel down the tube E, it is conducted by such tube 15 to a point above the pen-point, where it flows upon the pen-point and passes without difficulty to the paper which is being written upon. The eye f', at the rear end of the rod F, forming, in effect, a shoulder, by coming in contact with the pen-section C prevents any 20 strain being communicated to the tube E, such as would cause said tube to be drawn out of its place in the pen-section. Since the air is perfectly supplied to the pen by means of the tube E, the flow of ink to the pen-point does not depend upon the point being raised from the passage c' beneath it, and I am consequently enabled to use a pen having elastic 25 nibs and one which writes more easily than the pens required by all the fountain-pens of which I am aware. The tube K being merely forced into its socket can, like all the other parts of my pen, be readily removed for cleaning. 30 It is obvious that various changes can be made in the above-illustrated construction which will be within the scope of my invention. 35 Having thus described my invention, what I claim is—

1. In a fountain-pen, the combination of a pen-body, a tube extending longitudinally of the chamber in said pen-body and being readily removable therefrom, and a rod loosely 40 mounted in said tube and adapted to fall back and forth therein.

2. In a fountain-pen, the combination of a pen-body, such body having a tapering socket a tube extending longitudinally of the chamber in such body, said tube being engaged solely by friction with the said tapering socket in said body, and a rod loosely mounted in said tube.

3. In a fountain-pen, the combination with a pen-body, a tube extending longitudinally of the chamber in said body, and a rod loosely mounted in said tube, said rod being adapted to fall from said tube, and to break air-bubbles formed in said chamber. 45

4. In a fountain-pen, the combination of a pen-body, a tube extending longitudinally of the chamber in said body, and a rod loosely mounted in said tube, said rod having a shoulder to prevent said rod from completely entering said tube. 50

5. In a fountain-pen, the combination of a pen-section having an ink-passage beneath the pen-point, and having an air-passage above the pen-point, said air-passage having an opening upon its side opposite to said pen-point. 55

6. In a fountain-pen, the combination of a pen-section having an ink-passage beneath the pen-point, and a tube inserted in said pen-section above the pen-point, said tube having an air-receiving opening upon its side opposite to said pen-point. 60

7. In a fountain-pen, the combination of a pen-section having an ink-passage beneath the pen-point, and a tube inserted in said pen-section above the pen-point, said tube having an air-receiving opening upon its side opposite to said pen-point, and having an opening adjacent to the upper surface of the pen-point. 65

8. In a fountain-pen, the combination of a pen-section having an air-admitting passage therein, a rod mounted in said passage and extending outside the pen-holder, so as to be capable of operation while the parts of the pen-holder are assembled. 70

9. In a fountain-pen, the combination of a pen-section having an air-admitting tube therein, and a rod mounted in said tube, and having a handle extending through a slot in said tube. 75

10. In a fountain-pen, the combination of a pen-section, an air-admitting tube mounted in said section, a rod extending through said tube, and having a handle extending through a slot in said tube, said rod having a shoulder adapted to engage with the pen-section to prevent the withdrawal of said tube. 80

11. In a fountain-pen, the combination of a pen-section having passages above and beneath the pen, cleaners mounted in said passages and connected together, one of said cleaners having means for engagement that is accessible when the parts of the pen are assembled. 85

In testimony that I claim the foregoing I have hereunto set my hand. 90

JOHN SOPER PURDY.
